UNITED STATES PATENT OFFICE

PERRY F. GRUVER, OF AMARILLO, TEXAS

CYLINDER AND PISTON

Application filed April 27, 1929. Serial No. 358,596.

This invention relates to cylinder and piston construction, the primary object of the invention being to provide novel means for reducing friction between the piston and walls 5 of the cylinder in which it operates, to the minimum, and at the same time insure a compression tight contact between the piston and cylinder walls.

Another object of the invention is the provision of a rectangular cylinder and a rectangular piston operating in the cylinder, the rectangular construction presenting wide surfaces to accommodate anti-friction rollers.

A still further object of the invention is 15 to provide a roller cage including angle bars fitted in the corners of the piston, the bars being constructed to insure a close fit insuring against the loss of compression.

With the foregoing and other objects in view which will appear as the description proceeds, the invention resides in the combination and arrangement of parts and in the details of construction hereinafter described and claimed, it being understood that changes in 25 the precise embodiment of the invention herein disclosed, may be made within the scope of what is claimed, without departing from the spirit of the invention.

Referring to the drawing:

Figure 1 is a longitudinal sectional view through a cylinder and piston constructed in accordance with the invention.

Figure 2 is a longitudinal sectional view through a cylinder and piston constructed in accordance with the invention and showing the piston at the upper end of its stroke.

Figure 3 is a sectional view taken on line 3-3 of Figure 2.

Figure 4 is a fragmental detail view of one 40 of the angle bars forming a part of the roller cage.

Referring to the drawing in detail, the reference character 5 designates a pump cylinder which is preferably rectangular in cross section, and as shown is cut away on its inner surfaces providing recesses for the reception of the roller cages, which are indicated by the reference character 6.

Each of these roller cages embodies angle 50 bars 7 that fit within the corners 8 of the

cylinder so that the angle bars may move longitudinally of the cylinder but at the same time provide a compression tight fit between the angle bars and cylinder.

Extending from the angle bars are lugs 9 55 or pintles that fit into the ends of the hollow rollers 10 to hold the rollers in proper spaced relation with each other to permit the free rotation of the rollers. While I have shown the rollers as hollow, it is of course understood that these rollers may be solid with 60 openings at their ends to receive the lugs 9.

The piston operating in the cylinder is also rectangular in cross section and is of a size to closely fit within the cylinder and engage 65 the rollers 6 in such a way that a compression tight fit between the piston and rollers is insured. As shown, the roller cages are of lengths less than the length of the cylinder 70 so that the roller cages may move longitudinally of the cylinder to reduce friction between the piston and rollers with which the piston contacts.

While I have shown and described the invention as used in a pump construction, it is 75 to be understood that the idea of the invention may be carried out in the construction of an internal combustion engine.

I claim:

1. In a device of the character described, so 80 a cylinder rectangular in cross section, a piston operating in the cylinder, roller cages positioned within the cylinder to move longitudinally thereof, and said piston engaging the rollers of the roller cages.

2. In a device of the character described, a cylinder, roller cages mounted within the cylinder, each of the roller cages including angle bars fitted in the corners of the cylinders, lugs extending from the angle bars, 90 rollers having their ends fitted over the lugs to support the rollers, and a piston operating in the cylinder and contacting with the rollers.

3. In a device of the character described, 95 a cylinder rectangular in cross section, said cylinder having its inner surfaces cut away defining compartments, angle bars fitted within the corners of the cylinders, lugs on the angle bars, hollow rollers, said lugs ex- 100

tending into the hollow rollers to support the rollers, a piston operating in the cylinder and engaging the rollers to reduce friction between the piston and cylinder.

In testimony that I claim the foregoing as my own, I have hereto affixed my signature.
